UNITED STATES PATENT OFFICE.

JOHN E. MITCHELL, OF ST. LOUIS, MISSOURI.

BOLL-BREAKING AND COTTON-SEPARATING MACHINE.

1,368,823.

Specification of Letters Patent. Patented Feb. 15, 1921.

Application filed November 7, 1919. Serial No. 336,295.

To all whom it may concern:

Be it known that I, JOHN E. MITCHELL, a citizen of the United States, residing in the city of St. Louis and State of Missouri, 5 have invented new and useful Improvements in Boll-Breaking and Cotton-Separating Machines, of which the following is a specification.

This invention relates to a combined boll 10 breaking and cotton separating machine of a type particularly designed for use in the field by small planters.

The broad object of the invention is to provide novel means for permitting the free 15 discharge of hulls, trash, sticks, etc., from the working chamber of the machine without at the same time permitting the loss, or escape of cotton.

With the above general object in view, 20 the invention resides in the novel construction and arrangement of the hull board and parts immediately associated therewith combined with means for inducing an upward current of air past the saw cylinder, 25 whereby the free discharge of trash is permitted through the discharge opening from the working chamber while small wads, or locks of cotton will be drawn upward by the air current, or, at least held suspended, and 30 be prevented from escaping with the trash.

The present invention is in effect an improvement of the idea embodied in the patent to Elliott No. 1,081,594, dated December 16, 1913, wherein a blast of air is dis- 35 charged from the bottom of the hull board toward the saw cylinder for the purpose of blowing the cotton against the teeth of the latter while not interfering with the free discharge of the hulls. In operation, how- 40 ever, this idea was not found to be entirely satisfactory in preventing a discharge of light, round locks, or wads, of cotton from the working chamber by reason of the fact that the saw teeth would not always take 45 hold of them when they were blown over in contact with the saw cylinder; whereas, with the proper amount of suction up through the discharge space, cotton of the character referred to is lifted enough to pre- 50 vent its falling, or being knocked out through the discharge space.

In the use of a machine of this character in the field, it is necessary to provide for dealing with a considerable quantity of 55 sticks, by reason of the fact that when the

planters have the machine to depend upon for cleaning the cotton they gather the cotton very rapidly, stripping parts of the stalk along with the bolls, whereas, without the machine, when the cotton must be taken 60 to the market just as it is gathered, the planters naturally take more time in gathering, or picking it, owing to the higher price obtained for the cleaner grades of cotton.

In consequence of having an extra 65 amount of sticks and trash to contend with in operating in the field, it is necessary to provide a very free and open space for the escape of the sticks and trash through the opening between the bottom of the hull 70 board and the saw cylinder.

To provide this extra large opening, and at the same time prevent the waste of small locks, or wads of cotton, which would ordinarily pass through with the refuse, I use 75 a fan, or other suction device for causing a light current of air to flow up through the discharge space between the bottom of the hull board and the saw cylinder, so as to cause such wads, or locks, of cotton to be 80 drawn up and toward the saw cylinder, or to suspend the same, as it were, in the working chamber, to prevent their falling through with the trash, so that they may be engaged by the saw cylinder. 85

There is very little tendency for large locks, or wads of cotton to discharge with the hulls and trash, as such locks always fall against the saw cylinder and are easily caught by the teeth of the saw and carried 90 up out of the discharge space. But small round locks, or wads of cotton which are often encountered and sometimes without having seeds in them, do not readily hang, or catch on the teeth of the saws, and easily 95 roll out through the discharge opening with the trash and hulls. Such bodies of cotton, however, are very light for their size,—especially when they contain no seeds,—in proportion to the hulls and sticks, so that 100 I have found it to be a simple matter to induce a current of air up through the discharge space to prevent the discharge, or loss, of such bodies of cotton as referred to, but at the same time not interfere with the 105 free discharge of the hulls, sticks, and other trash.

Having thus defined the purpose and general character of the invention, I shall now describe the same in detail, referring to the 110

accompanying drawing, in which the figure is a vertical sectional view through a machine constructed according to my invention, the driving mechanism for operating the 5 various elements of the machine not being shown, as the construction and arrangement of these parts are within the understanding of all those familiar with this art.

The numeral 1 indicates a casing inclosing 10 the operating mechanism, which casing is supported on a base 2. Mounted on the casing is a feed hopper 3, in the bottom of which are rotatably mounted feed rollers 4. Below the feed rollers is mounted the boll- 15 breaking cylinder 5, which is partly surrounded by a screen 6. Plates 7 and 8 suitably mounted in the casing 1 in spaced relation provide an outlet 9 from the boll-breaking chamber 10, in which the boll breaker 5 is mounted, and the upper of these plates, 8, is continued to form a semicircular deflector 11 to direct the products from the breaking chamber on an imperforate hull-board 12, which is mounted below the plate 7. A saw 20 cylinder, 13, kicker roll 14 and doffer brush 15 are mounted in the casing in a well known manner, and as shown in various of my prior 25 patents, the doffer brush removing the cotton from the saw cylinder and discharging it through an opening 16 in the casing of the machine. Between the lower end of the hull-board 12 and the saw cylinder 13 a space 17 is provided for the escape of hulls, trash and sticks from the working chamber 18, and 30 the hull-board is made adjustable, as usual, to vary the size of this opening according to the character of cotton being treated in the machine. Mounted on the top of the casing 1 is a fan casing 19, having a discharge flue 20, and inclosing a fan 21, said fan casing communicating with a small chamber 22 mounted on the top of the casing 1 and communicating at its lower end with the interior thereof, as indicated in the 35 drawing.

In operation the cotton, as it is picked, or gathered in the field, is dumped from baskets, or bags, into the hopper 3 and is uniformly drawn from the hopper by the 40 feed rollers 4. As it is drawn through between the rollers 4, the fingers of the breaking cylinder pick the cotton off and carry it around against the screen 6, the sand or fine dirt passing through the screen while the 45 cotton, hulls, and sticks are thrown outward through the outlet 9 into the working chamber 18 and are directed by the deflector 11 onto the hull-board 12, from which the product slides across the discharge space 17 into contact with the saw cylinder. The cotton 50 is caught by the teeth of the saw cylinder and carried upward, while the loose hulls and sticks fall out through the discharge space 17. The hulls adhering to the cotton 55 carried up by the teeth of the saws are

knocked loose by the kicker roll 14 and thrown back onto the hull-board 12, while the cotton is carried through underneath the kicker roll and is removed from the saw cylinder by the doffer brush 15 and discharged through the opening 16. The suction fan 21 causes a current of air to be drawn up through the discharge space 17, as indicated by arrows, which current draws upward, or holds in suspension, the small 70 wads, or locks, of cotton, so that the latter are prevented from falling out of the working chamber with the trash, as previously described, and in time will be caught up by the saw cylinder in the same way as the other 75 cotton in the working chamber.

It will be understood, of course, that the current of air induced by the fan 21 will be so regulated as not to have a force sufficient to draw the cotton out of the working 80 chamber, but will be merely of a strength to arrest the downward movement of the cotton and impart only slight upward movement thereto, thus holding the small wads, or locks of cotton in the working chamber 85 until they have been caught up by the saw.

It is essential for this operation that the hull-board 12 be imperforate, as otherwise the upward current of air would not be confined to the space 17, and its effect in preventing the fall of the cotton through the opening 17 would be practically *nil*. Moreover, with an open-work, or grated, hull-board, such as is commonly illustrated in the prior art, the air current passing through the openings or spaces in the hull-board would seriously interfere with the proper passage of the cotton over the hull-board to the saw cylinder.

I claim:

1. In a machine of the class described in combination with a saw cylinder, an imperforate hull-board, the lower end of which defines the size of a discharge opening for hulls past the saw cylinder, and means for inducing an upward current of air through said discharge opening of sufficient strength to lift the cotton, or impede its fall, without interfering with the fall of the hulls through said opening.

2. In a machine of the class described, having a working-chamber for receiving the mixed cotton and hulls to be separated, a saw cylinder working in said chamber, an imperforate hull board, the lower end of which defines the size of an opening past said saw cylinder for the escape of hulls from said working-chamber, and means for inducing an upward current of air through said discharge opening and said working-chamber of sufficient strength to lift the cotton, or impede its fall, without interfering with the fall of the hulls through said opening.

3. In a machine of the class described,

- having a working-chamber, boll breaking mechanism operating to deliver the mixed cotton and hulls to said working-chamber, cotton separating mechanism including a saw cylinder working in said chamber, an imperforate hull board, the lower end of which defines the size of an opening past said saw cylinder for the discharge of hulls from said working chamber, and means for inducing an upward current of air through said opening and said working-chamber of sufficient strength to lift the cotton, or impede its fall, without interfering with the fall of the hulls through said opening.
- 5 4. In a machine of the class described, in combination with a casing, a boll-breaking chamber located therein, boll breaking mechanism mounted in said chamber, cotton-separating mechanism including a saw cylinder, mounted in said casing, the construction affording a working-chamber between the two sets of mechanisms, an upwardly-inclined chute leading from said boll-breaking chamber, a hull-board located beneath the upper end of said chute, the lower end of which defines the size of an opening past said saw cylinder for the escape of hulls from said working-chamber, a curved deflector surrounding the mouth of said chute above said hull-board, and means for withdrawing air from said casing whereby to cause a current of air to pass upward through said opening and working chamber.
- 10 In testimony whereof I have hereunto set my hand.
- 15 JOHN E. MITCHELL.
